UNITED STATES PATENT OFFICE.

JOHN J. GILLOOLY, OF NEW YORK, N. Y.

DESIGN FOR A DOLL.

Application filed October 18, 1923. Serial No. 7,538. Term of patent 14 years.

To all whom it may concern:

Be it known that I, JOHN J. GILLOOLY, a citizen of the United States, and a resident of the city of New York, borough of Manhattan, in the county and State of New York, have invented a new, original, and ornamental Design for Dolls, of which the following is a specification, reference being had to the accompanying drawing, forming part thereof.

The drawing illustrates a front elevation of a doll, showing my new design.

I claim:

The ornamental design for a doll, as shown,

JOHN J. GILLOOLY.
